UNITED STATES PATENT OFFICE.

AUGUST J. MOTTLAU, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC CURLING IRON.

Application filed November 14, 1925. Serial No. 69,037.

My invention relates to curling irons and particularly to electrically-heated curling irons.

An object of my invention is to provide a curling iron that shall be operatively flexible, simple in construction and easily manufactured.

Another object of my invention is to provide a curling iron having a tong member that shall be free of hair-catching projections and that shall have a spring member which serves jointly as a pivot and support for the tong member.

Another object of my invention is to provide a tong member for a curling iron which shall have its pivot point removed from the transverse axis of heating member whereby the tong member may be moved about said pivot substantially parallel with said tong member throughout its working movement.

In the accompanying drawings,

Fig. 1 is a view, in side elevation, of a curling iron embodying my invention, a member thereof being shown partially in longitudinal section.

Fig. 2 is a view, in cross section taken on the line II—II, of the device illustrated in Fig. 1,

Fig. 3 is a view, in cross section taken along the line III—III, of the device illustrated in Fig. 1,

Fig. 4 is a side view of the spring for supporting the tong member.

Fig. 5 is a partial view showing a modification of a portion of the device illustrated in Fig. 1.

Fig. 6 is a view in section taken on the line VI—VI of the device illustrated in Fig. 5.

Fig. 7 illustrates a modified form of spring for supporting the tong member, and

Fig. 8 is an assembled view of the modification shown in Figs. 5, 6 and 7.

Referring more particularly to Fig. 1, a curling iron device 11 comprises a relatively stationary cylindrical member 12 and a member 13 that is movable with respect to the member 12.

The stationary member 12 comprises a tubular casing 14, a ferrule 15 attached to one end thereof, a handle portion 16 secured to said ferrule, and a heating element 17 disposed within the tubular casing 14.

The member 13 comprises a tong portion 18, a spring 19 and a thumb rest 21 attached

to the lever end of said tong by rivets 22. The casing member 14 is hollow and closed at its outer end. The inner end is open in order to permit the heating element 17 to be inserted.

The ferrule member 15 is formed from a thin sheet of steel or of soft metal such as brass, by a process of pressing and drawing in a suitable die thereby forming a hollow cylinder having a depressed end portion 23. A slot 24 and a hole 25 are punched in the portion 23 to receive the tubular member 14 and the spring member 19, respectively. The handle 16 fits tightly into the open end of the ferrule 15.

The handle 16 is preferably made of a single piece of wood, although other materials such as hard rubber or fiber may be used. The portion of the handle 16 extending outwardly from the ferrule 15 is of bottle shape. The neck portion 27 thereof serves to permit the operator of the curling iron to obtain a good grip thereon, and the flange 28 at the top portion of said neck serves as a stop for the ferrule 15.

The handle member 16 is hollow to constitute recesses 29, 30 and 31, as is indicated by the broken lines.

The hollow portion 29, 31 is larger than the recess 31 extending towards the ferrule 15 in order that a swivel plug (not shown) may be inserted to engage a pair of terminals 32 and 33. An opening 34 extends laterally into the hollow portion of the handle in order that a screw member 35 may be inserted therein to engage a collar 36 which is attached to the heating element 17. A rectangular opening 37 and a circular opening 38 which is concentric with the longitudinal axis of the handle 17, are located in the ferrule end thereof and correspond with the slot 24 and the hole 25.

The heating element 17 extends into the tubular casing member 14 and is electrically insulated therefrom. The terminal members 32 and 33 for the element 17 are located in the hollow portion of the handle and are respectively connected to ends of the heating element 17. The terminal 33 is shown in enlarged section in Figs. 2, 3 and 6 and is shown by broken lines in Fig. 1. The terminal 32 as illustrated in Fig. 1, is concentric with the terminal 33. As the particular construction of the terminals and the heating element form no part of my invention, it

is deemed not necessary to describe them further in detail.

The tong member 18 is of U-shape in cross-section and the lever end 39 thereof is formed by making two elbow bends at 40 and 41 therein. The U section is deepest over the portion which registers with the tubular member 14 and becomes gradually shallower at the lever end 39.

16 The spring member 19 illustrated in Figs. 1 and 4 is of L-shape and is made preferably from thin strap spring steel. The ferrule end 42 of the spring 19 is bent whereby a resilient press fit is obtained when said spring member is registered with the rectangular hole 37 in the handle 16 and the slot 24 located in the ferrule 15. The rivets 22 secure the spring 19 to the tong member 18.

20 The spring 19 is so shaped that the tong engages the tubular member 14 at the outer end only. Since the spring member 19 supports the tong 18 and also serves as a pivot around which said tong 18 turns, the tong member is substantially parallel with respect to the tubular member throughout the operating movement of the tong. Parallel motion is effected because the point 43 of greatest flexure of the spring is located away 30 from the longitudinal and transverse axes of the tubular member 14 and also because the tong is not quite parallel with the member 14 when they are in engagement as shown in Fig. 1.

35 Relative parallel motion is an advantage, because when the tong member 18 is out of engagement with the member 14 and in position to permit hair to be placed between them in position for curling, and even pressure thereon is effected when the tong is released to approach the closed position as 40 illustrated in Fig. 1. The tong member is detached from the curling iron proper by merely sliding the spring 19 out of the slot 24.

In Figs. 5, 6, 7 and 8, I have shown modifications of certain of the details of the device of Fig. 1. The ferrule 44 has an integral outwardly extending portion 45 wherein the spring member 46, illustrated in Fig. 7, is located when the tong member 18 is in its operative position. The spring member 46 is made of strap spring steel bent to conform to the general shape 50 of the tong 18, and is attached to the tong member in the same manner as is the spring member 19 illustrated in Fig. 1. The tong member illustrated in Fig. 8 is attached to the curling iron proper by registering the 55 spring member 46 with the ferrule 44. Entrance of the spring 46 into the ferrule 44 is made from the handle side thereof through an opening 47. The point of greatest flexure of the spring member 46 is located approximately at the point 48.

The thumb rest 21 is made of a heat insulating material such as fiber or bakelite and is attached to the lever portion 49 of the tong 18 by the rivets 22. It is rectangular in shape and has sufficient surface to insure ample bearing area for the operator's thumb and has sufficient thickness to prevent the surface thereof from attaining a high temperature.

My invention provides a curling iron having 75 a tubular member, a ferrule attached to one end thereof and a handle portion secured to the ferrule and a detachable tong member which may be secured to the ferrule by reason of a spring which is attached to 80 the tong member. The spring serves as a means for holding the tong to the curling iron proper and also serves as a yielding connection thereto by means of which the tong member may be moved substantially 85 parallel relatively to the tubular member.

Various other modifications of my invention may be made without departing from the principle and scope thereof. I desire, therefore, that only such limitations shall be 90 placed thereon as are imposed by the prior art.

I claim as my invention:

1. In combination, in a curling iron, a tubular member, a tong member co-operating therewith and a spring member for pivotally supporting and biasing said tong member to operatively engage said tubular member.

2. In combination, in a curling iron, a tubular member having a ferrule at one end thereof, a tong member co-operating with said tubular member and a spring member connected to said tong member and to said ferrule and constituting the sole support for 105 the tong member.

3. In combination, in a curling iron, a tubular member, a tong member co-operating therewith, a resilient means constituting the sole support for said tong member, said resilient means being effective to yieldingly retain the tong member in operative relation with said tubular member.

4. In a curling iron, in combination, an electric heating element, a tubular member 115 for enclosing said electric heating element, a ferrule secured thereto, a tong cooperating with said tubular member, and a removable resilient tong-supporting member operatively connected to said ferrule and constituting the sole support for the tong.

5. In a curling iron, in combination, a tubular member having a heating element therein, a ferrule secured to one end thereof and having an aperture therein, a handle 125 operatively associated with said ferrule and having terminals for said heating element enclosed therein, a tong cooperating with the tubular member, and a spring member for movably supporting the tong member and 130

for yieldingly pressing the tong member against the tubular member, said spring member being resiliently and frictionally engaged with the aforesaid aperture.

5. 6. In a curling iron, in combination, a tubular member, a ferrule secured to one end thereof and having an aperture therein, a handle associated with said ferrule, a tong cooperating with said tubular member, and 10 a spring member for pivotally supporting the tong member, the pivot portion of said spring member being removed from the longitudinal axis of said tubular member whereby the tong may be moved about said 15 pivot portion to effect substantially parallel motion between the tong and the tubular member throughout the normal working range of said tong.

7. A curling iron comprising a stationary

member, a ferrule thereon having an aperture extending longitudinally therein, a movable tong member, and a spring secured to the tong member and adapted to be received in the aperture in the ferrule.

8. In combination, in a curling iron, an 25 elongated cylinder, a ferrule having an aperture extending parallel with the major axis of said cylinder, a tong, a handle engaging said ferrule, and a spring member having a portion extending into said aperture and 30 having another portion secured to the tong and constituting the sole pivotal support therefor.

In testimony whereof, I have hereunto subscribed my name this 29th day of October, 1925.

AUGUST J. MOTTLAU.
